US00D745397S

(12) **United States Design Patent**
Gogola et al.

(10) **Patent No.:** **US D745,397 S**
(45) **Date of Patent:** ** *Dec. 15, 2015

(54) **BOTTLE**

- (71) Applicant: **Rexam Beverage Can Company**,
Chicago, IL (US)
- (72) Inventors: **Michael Gogola**, Itasca, IL (US); **Rex Villasin**, Schaumburg, IL (US); **Thomas Cotton**, London (GB)
- (73) Assignee: **Rexam Beverage Can Company**,
Chicago, IL (US)
- (*) Notice: This patent is subject to a terminal disclaimer.
- (**) Term: **14 Years**

(21) Appl. No.: **29/466,959**

(22) Filed: **Sep. 13, 2013**

(30) **Foreign Application Priority Data**

- Mar. 13, 2013 (EM) 002202093-0003

(57) **CLAIM**

We claim the ornamental design for a bottle, as shown and described.

DESCRIPTION

FIG. 1 is a perspective view of the design for a bottle;
FIG. 2 is a side elevation view of the design for a bottle; and,
FIG. 3 is a top plan view of the design for a bottle.
Features shown in broken lines in the drawings are not part of
the claim.

1 Claim, 3 Drawing Sheets
